ABSTRACT: A blank construction for making packages which contain a plurality of articles. The blank comprises a flat, paperboard base member and a sheet of heat shrinkable film secured to one surface of the base member. In accordance with the method of forming the blank, air is blown between the shrinkable film and the base member to provide a sufficiently large opening to permit the lateral insertion of groups of articles. The apparatus includes parallel feeding conveyors whereby packages may be formed continuously with cam means being provided to impart the lateral movement to the groups of articles. After the articles are in place, the heat shrinkable film is shrunk over the tops of the articles as they pass through a shrink tunnel which may be mounted on the conveyor which feeds the blanks.

METHOD OF MAKING A PACKAGE

This invention relates to a blank construction suitable for use in making packages which contain a plurality of articles and to a method and apparatus for forming the same. More particularly, the invention relates to a blank construction comprising a paperboard base member and a sheet of heat shrinkable film secured to one surface thereof which is preferably formed into a heat shrunk package in accordance with the method and apparatus disclosed herein.

Heretofore it has been customary to make packages having a tubular heat shrinkable film member which completely surrounds a plurality of articles that are carried on a tray made from paperboard and sometimes referred to in the trade as a "shipper." Difficulty has been experienced in handling the components of this package so as to place the tubular heat shrinkable film in an encapsulating relationship with respect to the shipper and the articles to be held thereby.

The present invention overcomes the handling problems inherent in the aforementioned type packages by attaching the heat shrinkable film as a sheet to the uppermost surface of the paperboard tray prior to its formation into a tray. The attachment of the film to the tray is such that it facilitates easy separation thereof whereby articles to be packaged may be inserted therebetween.

In a preferred form of the present invention, the separation of the heat shrinkable film from the paperboard tray is effected pneumatically, i.e. by blowing air to fluff up the shrinkable film whereby the articles may be inserted. It is also preferred to separate the heat shrinkable film by deploying the means to effect separation on one side of the blank and to insert the articles from the other side of the blank.

One structural feature which facilitates separation of the heat shrinkable from the paperboard base member is to have the heat shrinkable film folded under on itself prior to being secured to the paperboard base member. Another feature which facilitates mass production of the blank construction of the present invention is to have the length of the heat shrinkable film substantially coextensive with the length of the base member whereby each may be severed simultaneously. The blank is scored and cut to permit its folding into an open top tray and the film is attached exteriorly to a pair of spaced parallel score lines so that the film is secured to the inside of the sidewalls themselves.

The packages produced in accordance with this invention are preferably produced continuously. In accordance with a preferred form of the invention, the articles to be packaged are fed on one conveyor adjacent to the path of the blanks which are fed on another conveyor. Therefore, by redirecting the flow of articles on one conveyor, such as by cam means, the articles are fed into an opening between the heat shrinkable film and the paperboard base, the extent of lateral movement of which is controlled by folding up one of the sidewalls of the paperboard base itself.

The inherent advantages and improvements of the present invention will become more readily apparent upon considering the following detailed description of the invention and by reference will become more readily apparent upon considering the following detailed description of the invention and by reference to the drawings in which:

FIG. 1 is a top plan view, somewhat schematic in nature, showing the general arrangement of components for the practice of the present invention;

FIG. 2 is a perspective view of the blank construction of the present invention;

FIG. 3 is a perspective view of the blank construction showing its position when placed on the blank conveyor;

FIG. 4 is a fragmentary perspective view demonstrating one step in the method of assembly of the package;

FIG. 5 is a fragmentary perspective view demonstrating another step in the method of assembly of the package; and,

FIGS. 6-9 are fragmentary perspective views demonstrating further steps in the method of assembly of the package.

Referring now to FIG. 1 of the drawings, there is illustrated a blank conveyor, indicated generally at 10, whose forward travel is from left to right as viewed in this figure. Blank conveyor 10 carries a plurality of blanks which are indicated generally at 12. An article conveyor 14, whose travel is also from left to right as viewed in FIG. 1, is preferably positioned substantially parallel to the blank conveyor 10 and driven at the same forward speed. A plurality of articles 16 are fed forwardly on the article conveyor 14 until they contact means for directing the articles laterally with respect to the forward direction thereof such as by contacts with cam means 17. The articles 16 may be of any desired shape or size but for purposes of description may be considered to be cylindrical articles such as cans of beer or the like.

15 Mounted on the side of conveyor 10 opposite from the article conveyor 14 is a blower means 18 the output of which is directed into a manifold 20. At spaced increments along manifold 20 there are provided a plurality of nozzle means 22 by means of which the individual blanks 12 may be opened in 20 a manner to be described hereinafter.

25 Referring now to FIGS. 2 and 3, the structure of an individual blank 12 will be described in greater detail. The blank is shown to comprise a paperboard base member 24 and a sheet of heat shrinkable film 26. In a preferred form of the invention, the heat shrinkable film 26 is folded lengthwise at 28 and 30 and folded under onto itself so as to be secured as at 32 to the paperboard base member 24 by a suitable adhesive or the like near or substantially adjacent the marginal edge portions of the paperboard base member 24.

30 As seen in FIG. 2, for example, the paperboard base member 24 is provided with a first pair of parallel opposed score lines 34 and 36 and a second pair of parallel opposed score lines 38 and 40 in order that the base member may be provided with upstanding sidewall members. Thus the opposed score lines 34 and 36 define a pair of end sidewall panels 42 whereas opposed parallel score lines 38 and 40 define a rear sidewall panel 43 and a front sidewall panel 44, respectively. In addition, two pairs of cuts 46 each of which are substantially in line with the score lines 38 and 40 define front sidewall panel flaps 48 and rear sidewall panel flaps 50 as can best be seen in FIGS. 4 and 5.

40 In operation, the blanks 12 are deposited on the blank conveyor 10 by any suitable means with the rear sidewall panel 43 and front sidewall panel 44 being erected, i.e. in the FIG. 3 condition, and in abutting relationship with another blank. At the station designated A the blank comes under the influence of the first nozzle 22 which projects air between the heat shrinkable film and the paperboard base member 24 so as to separate or fluff up the heat shrinkable film 26 with respect to the paperboard base 24. If desired and/or necessary means such as a mechanical duckbill may be used to be inserted between the heat shrinkable film 26 and the paperboard base 24 in order to ensure that separation between the two occurs. 45 In this respect, the point of attachment 32 of the heat shrinkable film 26 to the rear sidewall panel 43 and front sidewall panel 44 may be varied slightly for a particular package in order to accomplish a relatively easy separation of the heat shrinkable film from the base member.

50 At the station identified B a pair of oppositely rotating rotary tucker members indicated generally at 52 engage the front sidewall panel flap 48 and the rear sidewall panel flap 50 in order to flex each of the flaps inwardly in the position shown in FIG. 5. The blank is then in position to have adhesive

55 applied to selective areas on the end sidewall panel 42, such as at station C, whereby the latter panel may be adhesively secured to the outside surfaces of the front and rear sidewall panel flaps 48 and 50, respectively. While the application of adhesive is schematically indicated in FIG. 1 to be from nozzles or the like either the use of registered glue applicators or a glue applicator roller applied with a central portion of the end sidewall panel 42 suitably masked so as to avoid the reception of adhesive may be employed. By the use of any of these

60 means, the adhesive is applied to the selective areas 54. A conventional plow member 58 is then employed at station D in 65 further steps in the method of assembly of the package.

70 FIGS. 6-9 are fragmentary perspective views demonstrating further steps in the method of assembly of the package.

FIG. 1 to erect the end sidewall panel 42 and bring the glue pattern 54 thereon into contact with the front and rear sidewall panel flaps 48 and 50. Immediately thereafter at station E a compression conveyor belt 60 engages the outside surface of the end sidewall panel 42 to press it into sealing engagement with the front and rear sidewall panel flaps.

As can be seen in FIG. 1, concurrently with the operations being performed in stations B, C, D, and E, a cam means 17 directs groups of articles 16 laterally from conveyor 14 onto the blank conveyor 10. The nozzles 22 are located sufficiently frequently along the manifold 20 and have such a direction to ensure that the heat shrinkable film 26 remains separated or fluffed up with respect to the paperboard base member 24 to ensure a sufficiently large opening to admit the groups of articles 16 therethrough at the opposite side of the blank conveyor 10. At station F, when all of the articles 16 have been urged into their final position, a set of rotary tucker members 52 similar to those used to erect the first end sidewall panel 42 are employed to erect the opposite end sidewall panel. It should be noted that with the rear sidewall panel 43 and front sidewall panel 44 erected as the blanks travel on conveyor 10 these sidewall panels serve to guide the articles 16 as they are directed laterally through the opening in the blank 12 and from conveyor 14 to conveyor 10. Also, the erection of the end sidewall panel 42 adjacent the manifold 20 in station D serves as a stop means when the articles 16 reach the side of blank 12 adjacent manifold 20. The compression conveyor belt 60 serves to back up this stop means.

At station G adhesive is applied to the second end sidewall panel 42 by means of nozzles 56 or other glue applicator means after which the second end sidewall panel 42 is plowed into position at station H by means of plow 58. Thereafter, the second end sidewall panel 42 is engaged by a compression conveyor belt 60 located on the conveyor 14 side whereby the adhesive 54 is brought into sealing relationship with its associated front and rear side wall panel flaps 48 and 50. The package then enters a shrink tunnel 62 at station I which is conventional for purposes of the present invention and wherein the heat shrinkable film 26 is shrunk over the tops of the articles 16 so as to hold them tightly with the aid of base 24. The finished package as shown in FIG. 9 has an opening or gap at 64 which occurs at opposite sides of the package.

While the apparatus shown in FIG. 1 is somewhat schematic in nature, the number and position of nozzle means 22 in such as to ensure that the heat shrinkable film 26 remains separated or fluffed up with respect to the base member 24 to provide a sufficiently large opening at the end opposite the end from which the air is admitted to ensure that the group of articles 16 may be inserted from the opposite end to be cammed into their final position. The rotary tucker members, glue pattern applicator 56, and plow means 58 are all conventional insofar

as the present invention is concerned as is the heat shrinkable tunnel means 62. By attaching the heat shrinkable film as a sheet to the uppermost surface on the paperboard base prior to its formation into a tray, the handling problems inherent with the handling of a tube of heat shrinkable film are overcome. In addition, by having the heat shrinkable film attached to the paperboard base member near the marginal edge portions thereof facilitates its opening or fluffing up with the rear and front sidewall panels 43 and 44 being erected on the blank conveyor 10. The fact that panels 43 and 44 are erected also serves to guide the articles as they are being fed laterally onto the blank 12. The erection of the first end sidewall panel 42 adjacent the manifold 20 serves as a stop means for the articles 16 being loaded onto the tray. The folding of the sheet of heat shrinkable film under onto itself prior to the securement thereof to the base member is instrumental in obtaining the required separation or fluffing up of the heat shrinkable film with respect to the base member.

While presently preferred embodiments of the invention have been illustrated and described, it will be recognized that the invention may be otherwise variously embodied and practiced.

I claim:

1. A method of making a package for a plurality of articles from a blank comprising a paperboard base member and a sheet of heat shrinkable film overlaying said base member, said base member being provided with front, rear and a pair of end sidewall panels having flap panels at the ends thereof and having said sheet of heat shrinkable film secured to the upper surface of said base member substantially along the length of said end sidewall panels and flap panels, said method comprising the steps of
  - a. partially erecting said base member by folding said end sidewall panels to an erected position,
  - b. maintaining said partially erected position of said base member by blowing air between said heat shrinkable film and said base member to provide a sufficiently large opening to admit groups of said articles and while feeding a plurality of said blanks forwardly along a first path,
  - c. directing a group of said articles laterally with respect to the forward direction of said blanks through the opening of one of said blanks,
  - d. folding said flap panels having said film secured thereto inwardly over said base member,
  - e. folding one of said front and rear panels upwardly to cover said flat panels and sealing it thereto,
  - f. and heat shrinking said heat shrinkable film over the top and down a portion of the sides of said group of articles after they have been completely inserted between said heat shrinkable film and said base member.
